[57] ABSTRACT

A sling shot gun having a stock and barrel and a housing. Pivottally supported by the housing is an L-shaped member including a holding and release member and a horizontal portion supported to extend from the housing and to pivot between holding and release positions for holding and releasing the end of a resilient sling and a projectile. A biasing member is provided for biasing the holding and release member to its holding position. A trigger is supported by the housing to pivot between holding and release positions. The trigger is normally biased against the L-shaped member for retaining the holding and release member in its holding position. Movement of the trigger toward its release position releases the holding and release member to release the sling and the projectile. The holding and release member is positioned on top of the top portion that covers the open space at the rear end of the gun.

ELASTIC BAND TYPE GUN

BACKGROUND OF THE INVENTION

This invention relates to a sling shot gun that is simple, reliable and easy to use in that it is self-cocking.

SUMMARY OF THE INVENTION

The gun comprises a stock portion having a barrel for extending therefrom and a housing. Also included is a pivotally supported means including a holding and release member supported to extend from the housing and to pivot between holding and release positions for holding and releasing the end of a resilient sling means. Biasing means is provided for biasing the holding and release member toward its holding position whereby it is self-cocking. Trigger means is supported by the housing to pivot between holding and release positions and means is provided for normally biasing the trigger means toward its holding position for retaining the holding and release member in its holding position. Movement of the trigger means toward its release position, releases the holding and release member to release the sling. The pivotally supported means is supported to pivot about a first axis while the trigger means is supported to pivot about a different axis.

In the embodiment disclosed the pivotally supported means is generally L-shaped and includes the holding and release member and a generally transverse member. The trigger means includes a gripping portion and a second portion for engaging the transverse member for retaining the transverse member and the holding and release member in its holding position when the trigger means is in its holding position.

BRIEF DESCRIPTION OF THE DRAWINGS

FIG. 1 illustrates a front-side view of a sling shot gun; FIG. 2 illustrates a cross section of the housing with its holding and release mechanism;

FIG. 3 is a back view of the holding and release mechanism;

FIGS. 4 and 5 illustrate the retainer spring and trigger spring respectively.

DETAILED DESCRIPTION OF THE PREFERRED EMBODIMENT

Referring to FIG. 1, there is illustrated a gun 11 having a stock portion 13 and a barrel portion 15. In the embodiment disclosed the stock and barrel are integral with each other and are formed of wood. Attached to the stock portion by way of a rivet 17 is a metal housing 19, U-shaped in cross section. As illustrated in FIG. 2, the housing encloses a portion of a U-shaped slot 21 and a trigger slot 23 formed in the stock. Extending from one side of the housing to the other and through the slots are rivets 25 and 27 which act as pivot shafts for a pivotally supported member 29 and a trigger means 31 respectively. The pivotally supported member 29 is L-shaped and comprises a holding and release member 41 and a transverse portion 43 integral with member 41. As seen in FIG. 3, the member 27 has its lower end cut or notched in two places forming two side pieces 45 and 47 and a central piece forming the member 43. Member 43 is bent transverse to member 41 while side pieces 45 and 47 are bent in a hook shape configuration for surrounding the pivot shaft 25 and provide support for member 29 allowing it to pivot be-

tween a holding position illustrated in FIG. 1 and a release position shown in dotted form in FIG. 2.

The retainer spring 51, also shown in FIG. 4, is provided for normally biasing the member 29 in its holding position. In this position the member 41 is located in a position generally transverse to the axis of the barrel 15. Although not shown the back edge of the member 41 will be biased by the spring 51 to engage the back edge 21a of the slot 21, when in its holding position. In its release position, the member 41 will move in the forward direction generally parallel to the axis of the barrel 15 as illustrated in dotted form in FIG. 2. A relief 53 is cut in the back edge of the top of the housing 19 to allow the member 41 to move in a generally parallel position to the axis of the barrel 15 and flat against the top of the gun as illustrated in FIG. 2.

The trigger means 31 comprises a forefinger gripping portion 31a and an engaging and release portion 31b. The spring 55, also shown in FIG. 5, is provided normally biasing the trigger means in its holding position illustrated in FIG. 2. In this position, the top of the engaging portion 31b engages the bottom of the transverse member 43 thereby preventing the member 29 and hence the extending member 41 from moving to its release position. When the trigger means 31 is in its holding position, the gun 11 is ready to be loaded. In the preferred embodiment, the gun is provided with an elastic band 57 having one end secured to the forward end 15a of the barrel and the other end having a leather pouch 61 coupled thereto. This pouch is provided for holding, with the aid of member 41, a projectile 63 which is released by pulling the gripping portion 31a in a backward direction. In the holding position, as illustrated, the projectile 63 is located between the back portion of the member 41 and the pouch 61. When the gripping portion 31a is pulled backward, the trigger means 31 is moved to its release position illustrated in dotted form in FIG. 2. In this position, the engaging portion 31b moves from under the transverse member 43 allowing the member 29 and hence the extending member 41 to be pulled by the elastic band 57 to its release position thereby releasing the elastic band and the projectile.

Referring to FIGS. 2, 3, and 4, the spring 51 comprises the tail portion 51a held in position by the front portion of the rivet 27. Extending from the tail portion 51a is a cross member 51b having opposite ends coiled around opposite ends of the rivet 25. Thus the spring 51 biases and snaps the retainer or member 41 into its holding position after the projectile has been released. In one embodiment this spring is constructed of 0.020 diameter music wire spring steel.

The spring 55 has a hook portion 55a which hooks in front of the engaging portion 31b of the trigger. It has a lower portion which encircles the front surface of the slot 21. As can be seen in FIG. 5, the tail 55b is transverse to the portion 55c extending from the coil portion. As indicated above, the purpose of spring 55 is to bias or move the trigger into its ready or holding position after the projectile has been released. In one embodiment, the spring 55 is constructed of 0.035 diameter music wire spring steel.

Referring again to FIG. 1, the elastic band 57 is held in place by a transverse slot 15B formed in the face 15A of the barrel 15. This provides a simple arrangement for securing the band to the front face of the bar-

rel 15. With the band 57 having its ends extending from both sides of the barrel 15, the pouch is allowed to readily release its projectile without interference.

In the preferred embodiment, the gun 11 is provided for holding and releasing a projectile which may be a rock, marble, etc. It is to be understood, however, that the gun could be employed to shoot a rubber band itself rather than a rock or the like. In this respect the front surface 15a of the barrel 15 is notched inward with a relatively large radius of curvature for releasably holding one end of an elastic band, the other end of which is held by the member 41. In this embodiment, when the trigger is pulled, the member 41 will release the elastic band which then will be projected forward.

I claim:

1. A gun comprising:
a stock portion having an elongated barrel portion
extending therefrom,
an open space formed in said gun at a position spaced
rearward from the forward end of said barrel portion,
top and bottom openings leading to said open space
from the top and bottom sides of said gun respectively,
a pivotally supported member supported for pivotal
movement about a first axis between holding and
release positions,
said pivotally supported member including a holding
and release portion and a generally transverse portion,
said holding and release portion being adapted to
hold one end of a stretched resilient member,
said first axis comprising a support member located
within said open space at a position sufficient to
allow said holding and release portion to extend
through said top opening above the top of said gun
when said pivotally supported member is in its
holding position for holding a resilient member
having an end coupled to the forward end of said
barrel portion and to pivot to a forward position
generally parallel to the elongated axis of said bar-
rel portion when said pivotally supported member
is in its release position for releasing the resilient
member,
said transverse portion of said pivotally supported
member extending in a generally forward direction
relative to said holding and release portion when
said pivotally supported member is in its holding

position and extending generally downward into
said open space when said pivotally supported
member is in its release position,
first biasing means for biasing said pivotally sup-
ported member toward its holding position,
a trigger member supported to pivot about a second
axis between holding and release positions,
said second axis comprising a support member lo-
cated within said open space,
said trigger member including a gripping portion ex-
tending through said bottom opening to the bottom
side of said gun and a second portion which en-
gages said transverse portion of said pivotally sup-
ported member when it is in its holding position
and when said trigger member is in its holding position
for retaining said pivotally supported member
in its holding position,
said trigger member being adapted to pivot to its re-
lease position to locate its second portion forward
of said transverse portion of said pivotally sup-
ported member when said gripping portion is
pulled rearward to release said pivotally supported
member from its holding position,
second biasing means for biasing said trigger member
toward its holding position
a housing member including a top portion covering
a portion of said open space forward of said top
opening, said pivotally supported member comprising
a generally L-shaped member, said biased hold-
ing and release portion of said pivotally supported
member being positioned on top of said top portion
during the release of a resilient member when said
trigger member is not in engagement within the
transverse portion.

2. The gun of claim 1 wherein:
said first and second biasing members are separate
spring members.
3. The gun of claim 2 comprising the combination
therewith of a resilient sling:
a transverse slot formed in the forward face of said
barrel portion for securing one end of said resilient
sling thereto;
the other end of the sling with a projectile located be-
tween said other end and said holding and release
portion being adapted to be held and released by
said holding and release portion.

UNITED STATES PATENT OFFICE
CERTIFICATE OF CORRECTION

Patent No. 3,745,986 Dated July 17, 1973

Inventor(s) Ray E. Crowson

It is certified that error appears in the above-identified patent and that said Letters Patent are hereby corrected as shown below:

IN THE ABSTRACT

Line 3, cancel "and".

Line 4, cancel "a horizontal portion".

In the last line after "gun" and before the period (.)
insert --during the release of the sling--.

CLAIM 1

Column 4, line 32, after "said", add --second portion of
said--.

Column 4, line 33, cancel "within the" and add --with said--.

Column 4, line 34, after "portion" and before the period (.)
add --of said pivotally supported member--.

Signed and sealed this 1st day of January 1974.
